his Atty.*

UNITED STATES PATENT OFFICE

RICHARD A. HALLOCK, OF KANSAS CITY, MISSOURI.

GAME-BOARD.

1,215,799.

Specification of Letters Patent. Patented Feb. 13, 1917.

Application filed October 27, 1915. Serial No. 58,229.

To all whom it may concern:

Be it known that I, RICHARD A. HALLOCK, a citizen of the United States, residing in Kansas City, in the county of Jackson and 5 State of Missouri, have invented new and useful Improvements in Game-Boards, of which the following is a specification.

This invention relates to game boards. It has for its objects to produce a novel geometrically arranged playing surface or field over which pieces are moved in a game of opposition or capture or elimination of the respective pieces of the one side by those of the other; to provide for the movement of 10 the pieces straight up and down and laterally from top to bottom and side to side of the board and also in a diagonal direction from corner to corner thereof; and to attain certain advantages as will hereinafter 15 more fully appear.

The invention consists principally in marking or indicating on a game board intersecting vertical and horizontal lines and intersecting diagonal lines, the intersecting sections of certain vertical and horizontal lines coinciding with those of certain diagonal lines, and further in dividing the board into adjoining unitary squares, the line of boundary of each square constituting a playing line or line along which the pieces are moved, and sub-dividing each square by crossed diametrical and diagonal lines, the intersections of which coincide, said crossed lines also constituting playing lines, the 20 intersections of all lines being the points from and to which the pieces are played. The invention further consists in the constructions and arrangements set out in the appended claims.

40 The preferred arrangement of a board according to the invention is illustrated in the accompanying drawing forming part of this specification, and in which the playing surface or field is in the shape of a Greek cross, 45 the central portion of the cross comprising four of the sub-divided squares, and each arm or extension of the cross comprising two of such squares.

Referring now to the drawing, four 50 squares of the central field are indicated by the numerals 1, 2, 3 and 4, respectively. The top arm or projecting field of the cross comprises the two squares numbered 5 and 6, the bottom arm or field the two squares 7 and 8, 55 the left arm the two squares 9 and 10, and the right arm the two squares 11 and 12.

Each square is defined by border lines 13, 14, 15 and 16.

The respective squares are divided by the crossed diametrical lines 17 and 18 and the 60 crossed diagonal lines 19 and 20, at whose common intersection is a circle or spot 21 for indicating the position on which a piece may be placed and from and to which a piece may be moved in play.

65 At the intersections of the crossed diametrical lines with the respective border lines of the squares are circles or spots 22 on which pieces may also be placed and from and to which the pieces may be moved in 70 play. Circles or spots 23 are also marked at the corners of the squares.

The pieces used in the play may be similar to the disks or circular blocks used in the well-known game of checkers or of any 75 special design or shape as may be desirable.

As an illustration of a game which may be played upon the board of the character herein described, let it be supposed that the upper arm of the cross on the board shown 80 in the accompanying drawing represents a territory, or say a fortification, defended by a relatively small force, represented by three pieces which are placed at the points A, B and C, respectively, on which may be 85 termed the first line of defense, said territory or fortification to be attacked and captured if possible by a considerably larger force occupying all or a greater part of the spots on the central portion and lower and 90 side extensions of the board. By relatively proportioning the number of pieces on the opposing sides, and limiting the movement of the pieces of the larger force with respect to the range of movement allowed the 95 smaller force, and permitting the pieces of the smaller force to jump over and capture pieces of the larger force, while limiting the power of the pieces of the larger force to block or check the movements only of the 100 pieces of the smaller force, except possibly for the penalizing of a piece of the smaller force when failing to make a jump when an opportunity is afforded, the possibility of 105 winning or losing the game is substantially 110 equalized, provided, of course, the skill of the two players is equal.

The board is not limited to the playing of any one particular game, nor is the application of the invention confined to the particular form of the board shown, but the invention is characterized principally by an

arrangement of intersecting diametrical and diagonal lines from and to whose points of intersection the pieces are played, and it further comprehends a basic unit in the 5 form of a square which is divided by crossed diametrical and diagonal lines, by an assembled adjoining multiplicity of which or parts of which a game board is formed, the idea being carried out in a board of square, 10 polygonal or other geometrical design.

The board may also be lithographed in colors, different portions or fields thereof being in distinguishing colors, as also may be the different lines, to indicate limitation 15 and restriction of plays of the pieces. So, too, the board may have pictorial representations thereon according to the game for which it is to be particularly adapted. It is, therefore, to be understood these features 20 are within the contemplation of the appended claims.

I claim:

1. A game-board in the form of a cross, each arm of the cross comprising a multiplicity of adjoining unitary squares, each 25 square being divided by crossed diametrical

and diagonal lines, and the body of the cross comprising adjoining like unitary squares, the lines of boundary of said squares and said crossed lines connectedly constituting 30 continuous lines the length and breadth of the board, and the intersections of the respective lines constituting the points from and to which movable pieces are played on the board along said lines. 35

2. A game-board in the form of a Greek cross, each arm of the cross comprising two adjoining unitary squares, each square being divided by crossed diametrical and diagonal lines, and the central field bounded by said 40 arms comprising four adjoining like unitary squares, the lines of boundary of said squares and said crossed lines connectedly constituting continuous lines the length and breadth of the board, and the intersections 45 of the respective lines constituting the points from and to which movable pieces are played on the board along said lines.

In testimony whereof, I have hereunto set my hand.

RICHARD A. HALLOCK.
